Letter Patent No. 16 dated Feb. 12, 1861.

The schedule referred to in this Letter Patent and making part of the same.

To all whom it may concern:

I do know that I, Henry G. Thompson, of the City, County and State of New York, have invented or produced a new and original Design for a Pattern to be inwrought into Tapestry, Engraving and other Carpeting, in colors similar to those painted on the drawings accompanying this Specification, or in other colors substituted in the place of those painted on the drawings herewith: and I do hereby declare that the drawings accompanying this Specification, do give and convey to me, one skilled in the Art of Carpet weaving, a more defined and accurate idea of the nature of my invention than it is in the power of language otherwise to convey, and is sufficient to enable any one skilled in the art of Carpet weaving to use my invention.

That I claim as my invention and desire to secure by Letters Patent, is the Configuration of the Design herunto annexed, when made by being inwrought into Tapestry, Engraving or other Carpeting, in the form similar to the drawings accompanying this Specification.
